United States Patent Office.

MICHAEL C. TAYLOR, OF GRASS VALLEY, CALIFORNIA.

Letters Patent No. 98,122, dated December 21, 1869; antedated December 17, 1869.

IMPROVEMENT IN VARIABLE CUT-OFF FOR STEAM-ENGINES.

The Schedule referred to in these Letters Patent and making part of the same.

To all whom it may concern:

Be it known that I, MICHAEL C. TAYLOR, of Grass Valley, county of Nevada, State of California, have invented an Improved Variable Cut-Off for Steam-Engines; and I do hereby declare the following description and accompanying drawings are sufficient to enable any person skilled in the art or science to which it most nearly appertains to make and use my said invention, or improvement, without further invention or experiment.

My invention relates to that portion of the mechanism of a steam-engine, by which the admission of steam to the cylinder is regulated, and consists in an improved device, by which the steam is cut off, after the piston has accomplished a portion of its stroke.

This is done by two cams, which act upon the valve-stem, more or less directly, one of which opens the valve, and the other, following it, moves it still further, and closes the steam-port, but leaves the exhaust-port slightly open.

The last, or cut-off cam, is attached to a cylinder, having spiral grooves on the inside.

A follower, or plunger, having projections which fit these grooves, is moved back or forward, by a hand-wheel and screw, and makes the distance between the cams greater or less, so that the point at which steam shall be cut off is easily changed and regulated.

Referring to the accompanying drawings—

Figure 1 is a longitudinal vertical section.

Figure 2 is an end view.

Similar letters of reference in each of the figures indicate like parts.

A is a slide, which connects with the valve, and has a space, formed by the shoulders or projections B B', within which the cams C and D turn, and, by striking these shoulders, move the valve backward and forward.

The cam C has a short, hollow shaft, E, and may be actuated by a mitre-gear, or other suitable device.

The cam D is fastened to a hollow cylinder, F, which has the spiral grooves *a* on the inside.

A follower, G, is fitted to move within this cylinder, and has projecting lugs or feathers *c*, which fit into the grooves *a*, and, as the follower is moved toward one end or the other, the cylinder will be turned, and the cam D brought nearer to or removed from the cam C.

The follower is moved by means of a long screw, H, which is attached to one side of the follower by a

swivel, *d*, which allows the follower and cylinder to turn, without turning the screw.

The screw passes freely through the end of the cylinder, as shown at I, and then passes through a nut, J, which is turned within its stationary bearing K, by a hand-wheel, L, so as to move the follower from one end to the other of the cylinder.

To prevent the friction of the follower from rotating the screw, a groove is cut, longitudinally, in the lower part of the screw, and the top of the post M projects into it, sufficiently to prevent the screw from turning, thus making its motion merely forward and back.

In order to rotate the cylinder F, follower G, and the cam D, a square shaft, N, is fastened to the follower, on the side opposite the screw, and passes through the hollow shaft E of the cam C, fitting so that it must move with it.

The operation is as follows:

The engine being in motion, the cam C, striking one of the shoulders B, moves the valve so far as to open the steam-port on one side, and the exhaust-port at the opposite end, so that the steam follows the piston, till the cam D strikes the same shoulder, and moves the valve still further along, entirely closing the induction-port, but still leaving the exhaust-port slightly open; the piston then completes its stroke, by the expansion of the steam already in the cylinder; the cams continue their revolution, strike the other shoulder B', with a similar result, at the other end of the engine-cylinder. By turning the hand-wheel L, as previously described, the cams are brought nearer together, or are moved further apart, this being done without stopping the engine, and the point at which steam is cut off is regulated.

Having thus described my invention,

What I claim, and desire to secure by Letters Patent, is—

The arrangement, with reference to the projections B and B', and the cam C, of the cylinder F, provided with the cam D, and spiral grooves *a*, and the arrangement, within said cylinder, of the follower G, screw H, and sliding stem N, whereby the position of the cam D, relatively to C, may be readily adjusted, substantially as described.

In witness whereof, I have hereunto set my hand and seal.

Witnesses: MICHAEL C. TAYLOR. [L. S.]

WILLIAM STAINFORTH,
J. L. BOONE.
